UNITED STATES PATENT OFFICE.

MAX BUCHNER, OF MANNHEIM, GERMANY, ASSIGNOR TO THE FIRM OF C. F. BOEHRINGER & SOEHNE, OF MANNHEIM-WALDHOF, GERMANY.

ELECTROLYTIC REDUCTION OF NITRO OR OTHER COMPOUNDS.

SPECIFICATION forming part of Letters Patent No. 700,670, dated May 20, 1902.

Application filed November 18, 1899. Serial No. 737,494. (No specimens.)

To all whom it may concern:

Be it known that I, MAX BUCHNER, a citizen of the Empire of Germany, residing at Mannheim, in the German Empire, have invented certain new and useful Improvements in Electrolytic Reduction of Nitro or other Compounds; and I do hereby declare the following to be a full, clear, and exact description of the invention, such as will enable others skilled in the art to which it appertains to make and use the same.

This invention relates to the art of reduction, and in particular to the art of reducing nitro compounds to form the corresponding amines. Hitherto it has not been possible to readily accomplish such reduction by electrolytic methods and without waste and the formation of side products. This appears, *e. g.*, from the numerous experiments of Haussermann, Elbs, Gattermann, Noyes & Clement, Voigt, Loeb, and others. (See the compilation given in *Haber, Technische Elektrochemie*, page 522.) Thus, *e. g.*, it has been found on reducing nitrobenzene, which has hitherto been studied most exhaustively, that according to the solvent employed (such as concentrated sulfuric acid, dilute or alcoholic solution of sulfuric acid, concentrated hydrochloric acid, or acetic acid) or the material of the cathode (such as platinum, lead, or zinc,) final products consisting of varying quantities of anilin, benzidin, paraämidophenol, paraämidophenol sulfo-acid or anilin chlorid would be obtained.

A uniform unvarying and certain reduction of nitrobenzene to anilin by means of electrolysis has never been attained by any of the methods hitherto employed.

It is the object of this invention to overcome the difficulties thus set forth, said invention being based on the discovery which I have made that nitro compounds of the aromatic as well as the fatty class may be reduced to the corresponding amines if the same are dissolved or suspended in a suitable bath, such as water or an alcoholic aqueous solution of hydrochloric acid, and submitted to the action of an electric current in the cathode-chamber of an electrolytic cell or battery in the presence of tin. Moreover, I have found that under such conditions the yield will be almost theoretical. For this purpose

I may employ either a tin cathode directly or an indifferent cathode—such as, *e. g.*, a platinum, lead, carbon, or nickel cathode—together with a cathode electrolyte to which has been added a small quantity of a tin salt, such as stannous chlorid.

Under the method devised by me as based on my discovery when a cathode consisting of metallic tin is employed the tin will continue to go into solution so long as any unchanged nitro compound is present, the nitro compound being simultaneously reduced; but such dissolved tin will be immediately separated electrolytically and deposited on the tin cathode in the form of flakes or tin sponge. If, however, an indifferent cathode—such, *e. g.*, as a cathode of nickel—is employed and chlorid of tin is added to the electrolytic fluid in the cathode-space, metallic tin is first separated and deposited on the nickel cathode, which thereafter will act like a pure-tin cathode in the manner above set forth. It will be seen, therefore, that under this process a migration of positively-charged tin ions from the cathode into the cathode electrolyte takes place under conditions whereby the current is caused to simultaneously deposit tin ions at the same place.

Under my invention I am therefore enabled to reduce any desired quantity of a nitro compound to the corresponding amine with the aid of a very small quantity of tin, as I will show in Example 1^b below.

In reducing, *e. g.*, nitrobenzene to anilin it is therefore not necessary that an amount of tin equivalent to the amount of anilin produced is taken up by the electrolyte permanently and without being again separated by the current.

My method of reduction enables me to employ currents of high density and up to eighteen hundred amperes per square meter, so that the reduction may be carried out very rapidly. It is necessary to cool the cathode-space in order to avoid too intense heating.

When the reduction is carried out correctly according to my invention, the evolution of hydrogen will not be observed until almost the entire quantity of the nitro compound under treatment has been reduced, and after the completion of said reduction no tin will be found in the cathode-bath, so that it is

rendered possible to obtain the resultant bases in the form of their chlorids directly and in a pure condition.

It is to be understood that the metallic tin 5 is the direct and primary vehicle or agent of the reducing process; the function of the current is merely to precipitate the tin. In other words, the reduction of the compounds to be reduced is not effected by causing the 10 current to act upon them, but by the fact that the current acts upon the tin containing cathode-electrolyte, whereby the tin ions are discharged at the cathode and separated in the form of metallic tin. This metallic tin is, 15 however, speedily and continuously redissolved in the electrolyte so long as any unreduced compound capable of being reduced to an amin remains in the acid cathode-electrolyte. Where we start with a tin cathode and 20 without tin dissolved in the cathode-electrolyte, the tin from the cathode will rapidly go into solution so long as the electrolyte contains the reducible compound. From the acid electrolyte, which thus contains dissolved 25 tin and the resultant amin, there will be immediately precipitated metallic tin without evolution of hydrogen in the presence of high-density currents, such tin being again dissolved, and so on, the cycle of reactions being 30 repeated until no more reducible compound is left in the electrolyte.

My invention accordingly consists in subjecting nitro compounds to the action of an electric current in the cathode-space and in 35 the presence of tin, the tin being either the material of the cathode or in solution in the electrolyte; and my invention consists in such further features, details, and methods as will be hereinafter described, and pointed 40 out in the claims.

I will now give a detailed description of the preferred manner in which I carry out my invention. For this purpose I have selected the following examples:

45 *Example 1—Reduction of Nitrobenzene to Anilin.*

(a) *Employment of a tin cathode.*—An electrolytic cell is divided into an anode and a 50 cathode space by means of a suitable and convenient diaphragm. Into the former is poured sulfuric acid of thirty-per-cent. strength, and an anode of indifferent material is arranged therein. The cathode-space 55 is preferably provided with a stirring apparatus and a cooling-envelop of any suitable description. Into this cathode-space is introduced a solution of one hundred and fifty parts, by volume, of alcohol, fifty parts, by 60 volume, of fuming hydrochloric acid, and twenty-five parts, by volume, of nitrobenzene, or a mixture of twenty-five parts, by volume, of nitrobenzene with fifty parts, by volume, of fuming hydrochloric acid and fifty 65 parts, by volume, of water. The cathode is an electrode made of tin. When all the parts and materials are in place, the reduction is

effected by introducing an electric current of a density preferably of eighteen hundred amperes per square meter for a bath potential 70 of 6.5 volts. The reduction takes place very energetically without the evolution of hydrogen. The attendant great development of heat is counteracted by thorough cooling, while the cathode-bath is at the same time 75 maintained well mixed by suitably stirring. When the reaction process is completed, hydrogen begins to escape regularly, and thereby the end of the operation is indicated. The current is now cut off, the colorless cathode- 80 bath is separated from the tin sponge or flakes suspended therein by filtration, and the filtrate is evaporated. The residue is anilin chlorid in the form of a colorless crystalline mass, from which the anilin may be isolated 85 by known methods.

(b) *Employment of an indifferent cathode in the presence of a tin salt.*—The division of the electrolytic cell into an anode and a cathode space and the other arrangements of both 90 spaces are the same as described under 1^a, with these exceptions: that no tin cathode but an indifferent cathode, consisting, for example, of a net of nickel wire, is arranged in the cathode-space and that two parts, by 95 weight, of stannous chlorid are added to the cathode-bath, which consists of a mixture of twelve parts, by weight, of nitrobenzene with seventy-five parts, by volume, of fuming hydrochloric acid and fifty parts, by volume, of 100 water. On introducing into this electrolyte a current having a density of one thousand amperes per square meter for a bath potential of 8.5 volts metallic tin is first deposited on the nickel cathode, such deposited tin 105 acting exactly like the tin cathode described under 1^a. As soon as the evolution of hydrogen begins, thereby indicating the complete reduction of the nitrobenzene in the cathode-bath, further quantities of nitrobenzene, together with the amount of hydrochloric acid necessary to form anilin chlorid from the same, may be added to the bath, such further addition being repeated and continued until the solution is enriched with anilin chlorid to such an extent that it will directly solidify to a crystalline mass on cooling.

110 *Example 2—Reduction of Parannitrotoluene to Paratoluidin.*

The process is carried out as under Example 1^a, with the exception that the cathode-space is charged with a mixture of twenty parts, by weight, of parannitrotoluol, one hundred parts, by volume, of concentrated alcohol, (finespirits,) and ten parts, by volume, of fuming hydrochloric acid.

115 *Example 3—Reduction of Meta-Dinitrobenzene to Meta-Phenylenediamin.*

The process is the same as under Example 1, excepting that the cathode-space is charged with a mixture of twenty parts, by weight, of

meta-dinitrobenzene, two hundred and fifty parts, by volume, of rectified alcohol, (fine spirits,) and one hundred and fifty parts, by volume, of fuming hydrochloric acid.

5 *Example 4—Reduction of Alpha-Nitronaphthalin to Alpha-Naphthylamin.*

Here, too, the process described under Example 1 is followed, with the exception that 10 the cathode-bath consists of a mixture of twenty parts, by weight, of alpha-nitronaphthalin, two hundred and seventy parts, by volume, of rectified alcohol, (fine spirits,) and fifty parts, by volume, of fuming hydrochloric acid.

15 *Example 5—Reduction of Phenylnitromethane to Benzylamin.*

For this purpose the method set forth under 20 Example 1^a is carried out, with the exception that the cathode-space is charged with a mixture of five parts, by weight, of phenylnitromethane, one hundred parts, by volume, of rectified alcohol, (fine spirits,) and two hundred parts, by volume, of fuming hydrochloric acid.

It will be seen from a review of all the examples above given in illustration of my invention that the same, broadly considered, 30 consists in submitting a substance to be reduced, such as a nitro compound, to the action of an electric current in the cathode-space in the presence of tin, by which I mean that said action takes place either in the presence of a tin cathode or of an indifferent or neutral cathode combined with an electrolytic solution of tin or of a tin salt.

It should be noted that in the above examples there is always present a tin cathode, 40 since the indifferent cathode, as seen above, soon becomes coated with tin from the electrolyte solution. Therefore, though in one case we start with a tin cathode and a solution containing no tin salt or compound and 45 in the second case with an indifferent cathode and a solution containing tin in the form of a compound or salt of tin, in both cases the current acts on the body to be reduced in the presence of a tin cathode.

50 The process described is hence essentially the same whether we start the reducing process with a tin cathode or with another cathode and an electrolyte containing a tin salt. The course of the reduction is identical for both cases.

55 The process of the electrolysis consists in the electric neutralization of the ions at the electrodes. In thus giving up their electric charges the ions become converted into free 60 atoms or molecules, in which form they are capable of chemical reaction. At the moment of neutralization the ions may react upon one another or they may react upon other substances contained in the electrolyte. The 65 former process is termed "primary," the latter "secondary."

All electrolytic reductions are instances of

secondary reaction, both when the cathode employed is of indifferent material or when it is of material itself capable of reaction with the electrolyte. In the case of an indifferent cathode the hydrogen ions give up their positive charge directly to such cathode. In the other case the hydrogen ions give up their charge to the cathode material, (in the present case tin,) the metal of the latter continuously passing into the ionized state by solution in the acid electrolyte. The ions thereupon give up the charge received from the hydrogen ions to the cathode. In either case it is the 80 hydrogen which, being electrically neutralized by the current, reduces the nitro group. The tin employed in this reaction is continually redeposited after being dissolved.

The following electrochemical equations 85 will afford an insight into the nature of the reactions when a tin cathode is employed:

In the above equations R stands for any organic radical. The + and - signs indicate the electric charges of the ions. When, as 95 in the case of the metallic tin, + and - both are applied, it is to signify that the element concerned is in the molecular state. The sign affixed to the hydrogen indicates that the same is in the atomic state and has just been 100 discharged. The state represented by the expression

is to be regarded as one of only momentary 105 existence and has only been added for the sake of clearness. This combination of chemical reduction and electrolytic regeneration of the tin is a fundamental characteristic of my invention.

110 In the accompanying drawings I have represented one out of many possible forms of apparatus and electrolytic cells for carrying out the process involved in my invention.

In the drawings, A represents the anode-chamber containing the anode-electrolyte, and a the anode; C the cathode-chamber containing the cathode-electrolyte, and c the cathode, while d represents a diaphragm of any suitable material for separation of two 120 electrolytes, as will be readily understood. S represents a suitable stirrer arranged within the cathode-electrolyte, the spindle or shaft s of which may be connected with any suitable source of power by a belt and pulley B P, 125 as shown, or otherwise.

The cooling of the cathode-compartment may be carried out in any well-known manner, such as by cooling-coils and the like.

What I claim, and desire to secure by Letters Patent of the United States, is—

1. The process of reduction which consists in introducing a substance capable of being reduced by tin into an electrolyte capable of

- dissolving tin, and passing an electric current through the same in the presence of tin.
2. The process of reducing a nitro compound which consists in introducing such compound into an electrolyte capable of dissolving tin, and passing a current through the same in the presence of tin.
3. The process of reduction which consists in introducing a substance, capable of being reduced by tin into an electrolyte capable of dissolving tin, and passing an electric current through the same in the presence of a tin cathode.
4. The process of reducing a nitro compound which consists in introducing such compound into an electrolyte capable of dissolving tin, and passing an electric current through the same in the presence of a tin cathode.
5. The process of reduction which consists in introducing a substance capable of being reduced by tin into a cathode-bath containing a compound of tin, and passing an electric current through said bath.
6. The process of reduction which consists in introducing a substance capable of being reduced by tin into an electrolyte capable of dissolving tin, and passing an electric current through the same in the presence of tin and at the same time stirring and cooling.
7. The process which consists in introducing a substance, which is reducible, and an amine into an acid electrolyte capable of dissolving tin, and passing an electric current therethrough in the presence of a tin cathode.
8. The process which consists in introducing a substance which is reducible to an amine into an alcoholic acid electrolyte capable of dissolving tin and passing an electric current through the same in the presence of a tin cathode while stirring and cooling. 40
9. The process which consists in introducing a nitro compound to be reduced into a cathode-bath containing hydrochloric acid and in which is arranged a tin cathode and passing 45 an electric current through the bath.
10. The process which consists in introducing a nitro compound to be reduced into an alcoholic cathode - bath containing hydrochloric acid, and in which is arranged a tin cathode, passing an electric current through said bath and stirring and cooling the same.
11. The process which consists in introducing a nitro compound into a bath containing a stannous compound and hydrochloric acid 50 and having a cathode arranged therein and passing an electric current therethrough.
12. The process which consists in introducing a nitro compound into a cathode-bath containing hydrochloric acid and a stannous salt and having a cathode arranged therein, and passing an electric current therethrough while stirring and cooling. 60

In testimony whereof I affix my signature in presence of two witnesses.

MAX BUCHNER.
